UNITED STATES PATENT OFFICE.

FRANK KATZ, OF BROOKLYN, NEW YORK, ASSIGNOR TO ANCHOR MANUFACTURING COMPANY, OF NEW YORK, N. Y.

DESIGN FOR A PLATE OR SIMILAR ARTICLE.

Application filed January 15, 1926. Serial No. 16,104. Term of patent 3½ years.

To all whom it may concern:

Be it known that I, FRANK KATZ, a citizen of Poland, but has applied for naturalization papers in the United States, residing at Brooklyn, in the county of Kings and State of New York, have invented a new, original, and ornamental Design for Plate or Similar Article, of which the following is a specification, reference being had to the accompanying drawing, forming part thereof.

Figure 1 is a plan view of a plate showing my new design.

Fig. 2 is a side elevation thereof.

I claim:

The ornamental design for a plate or similar article, as shown.

FRANK KATZ.
